UNITED STATES PATENT OFFICE

123,926

DESIGN FOR A RADIO LOG DEVICE

John I. Steventon, Burlingame, and Stanley W.
Johnson, San Francisco, Calif.

Application July 10, 1939, Serial No. 85,938

Term of patent 7 years

To all whom it may concern:

Be it known that we, John I. Steventon and Stanley W. Johnson, citizens of the United States, residing respectively in Burlingame, county of San Mateo, State of California, and the city and county of San Francisco, State of California, have invented a new, original, and ornamental Design for a Radio Log Device, of which the following is a specification, reference being had to the accompanying drawing, forming a part thereof.

Figure 1 is a front face view of a radio log device, showing our new design, and

Figure 2 is an edge view of said radio log device.

We claim:

The ornamental design for a radio log device, as shown.

JOHN I. STEVENTON.
STANLEY W. JOHNSON.
